DEVICE OF THE CRANE TYPE FOR THE
LOADING AND UNLOADING OF MAGNETIC
MATERIALSFrancis H. Weeks, Haworth, and Richard E.
Weeks, Rutherford, N. J.

Application February 3, 1940, Serial No. 317,112

5 Claims. (Cl. 212—41)

This invention relates to new and useful improvements in devices of the crane type for the loading and unloading of magnetic materials.

For the purpose of loading or unloading materials, such as scrap iron and the like, and particularly when loading into ships' holds, loading receptacles are commonly used. These loading receptacles are transported back and forth between the place of loading and place of deposit of the load by means of a suitable crane type device, i. e., a device permitting the raising and lowering of a load and having the added capacity of moving such load in a horizontal or lateral direction. The loading receptacle, in the case of magnetic materials such as iron and the like, is usually filled or loaded by means of a suitable electromagnet. Hitherto it has been necessary to use two separate cranes, one for the loading receptacle and one for the loading magnet designed to fill that receptacle.

One object of the invention comprises, inter alia, a device of the crane type, equipped with a loading receptacle as well as a loading magnet, thereby eliminating the necessity for two separate cranes. This and further objects of the invention will appear from the following description read in conjunction with the drawing which represents a schematic illustration of one embodiment of the device in accordance with our invention.

As shown in the drawing, 1 represents an electromagnet of the type commonly used for loading magnetic materials such as scrap iron and the like. A magnet hoisting cable 2 actuated by drum 3 passes over and is suspended from roller 4 at the tip of arm or boom 5. A scale box or loading receptacle 6 resting for instance on the scrap pile 7, is secured to the receptacle hoisting cable 8 by means of chains 9, hooks 10 and ring or the like 11, the hoisting cable 8 being actuated by winding drum 12. Cable 15, actuated by winding drum 25 and adapted to move the magnet out of the way of the loading receptacle, is for example attached to the magnet at 14 adjacent the magnet suspension chains 13. A cable 16 suitably attached to the hoisting cable 2, such as by means of a block, ring or the like 27, is connected by way of roller 17, to an idler arrangement composed of counterbalance 18 moving on guide rail 19 secured to crane arm 20.

The structure in accordance with the invention is thus distinguished by the fact that it possesses both a magnet and a loading receptacle suspended from a common crane arm and pref-

erably at points in close proximity to one another.

In the practical application of our invention the loading receptacle is placed in the usual manner onto a suitable place of deposit by means of the crane. We have found it of advantage and prefer to use a loading receptacle of the releasable front-suspension, smooth bottom, scale box type as is for example disclosed in our Patent No. 2,159,065. Such scale box, having a smooth bottom, a back, two sides and an open end, carries suitable suspension means, secured to the back, and at least one suspension cable or chain, releasably attached to each side, near the front of the receptacle. This construction, apart from the advantages inherent in the same in connection with the loading of ships' holds, has the additional advantage that the receptacle may be placed onto a place of deposit, in a manner which will move the receptacle hoisting cable away from a vertical position, thus permitting the placing of the magnet with a minimum of interference with the rigging of the loading receptacle. This may be achieved by lowering the front of the scale box onto, for instance, a scrap pile, with the top of the box facing the crane, and thereafter tipping the box away from the crane onto the pile.

After the loading receptacle is lowered onto a convenient place of deposit, such as, for instance, the scrap iron pile 7, the hoisting cable 8 is slackened and the hooks 10, if a releasable front suspension receptacle is used, are thereupon released. The hoisting cable 8 is slackened to an extent sufficient to permit a relatively free movement of the boom or arm 5 without moving the receptacle from its place of deposit. The crane is now free to be used for the loading of the loading receptacle by means of the electromagnet.

Assuming the loading receptacle to have been placed on a pile of magnetic materials, such as a scrap iron pile, the magnet is swung into position and lowered onto the pile. The magnet may be moved into position by either swinging the same in the direction of the crane by means of the cable 15, or, by swinging the same in a substantially lateral direction by means of the boom or arm 5, or, alternatively, by a combination of both these expedients. It is equally possible to pick up magnetic material by means of the magnet from points beyond the loading receptacle in the direction away from the crane. This may be accomplished if desired by a tipping of the boom or arm 5. It will be thus seen that the magnet may be used to pick up loads from

practically every point of the scrap pile. For maximum efficiency, it is of advantage to so select the place of deposit for the receptacle, when placing the same directly onto the pile of magnetic material, that the magnet is able to pick up loads from points in the immediate vicinity of the receptacle. After the electro-magnet has picked up its load from the pile, the magnet is swung into position above the loading receptacle, whereupon, after the lowering of the magnet to a suitable height, the material transported by the same is released into the loading receptacle by cutting off the current supply to the magnet.

The afore-described procedure, of swinging the magnet into loading position, picking up a load of magnetic material, transporting such load to a point above the receptacle and releasing the load into the same, is repeated until the loading receptacle is substantially filled. The crane must now be made ready to function as a loading crane in combination with a loading receptacle. For this purpose it is necessary to move the magnet and preferably also the magnet hoisting cable out of the way of the loading receptacle. This may be accomplished in various ways. As illustrated in the drawing the magnet and magnet hoisting cable are moved out of the way of the loading receptacle by means of the cable 15 actuated by the winding drum 25. The magnet is pulled in by the cable 15 and the magnet hoisting cable 2 is preferably slackened. Though not absolutely necessary it is of advantage to suitably pull back the slackened magnet hoisting cable 2 which may be accomplished as illustrated in the drawing in a substantially self-adjusting manner by means of the cable 16 secured to the magnet hoisting cable 2 by means of the block or ring 27. The slack will be automatically pulled in by the counterweight 18 slidably engaged on track 19; the weight is attached to the cable 16 which passes over a roller or the like 17. The position of the magnet hoisting cable and idler, when the magnet hoist is in substantially slackened position, is, for instance, illustrated in the drawing in dotted outline.

Once the magnet, preferably together with its hoisting cable, is out of the way, the crane may be used in the ordinary manner for transporting the loading receptacle to the place where its load is to be deposited, such as a ship's hold or the like. When using the preferred releasable front suspension type receptacle, the disconnected suspension cables or chains must be re-attached before the loaded receptacle is lifted.

Though we have described, in the specific illustrative embodiment of our invention, a cable, attached to the magnet or to the magnet hoisting cable, as the means for moving the magnet and receptacle hoisting cable away from each other, it is possible, and within the purview of our invention, to use any other suitable means for this purpose. Instead of moving the magnet, preferably together with the magnet hoisting cable, away from the receptacle hoist, as hereinbefore described in connection with the drawing, it is sometimes of advantage and specific practices may recommend either a procedure in which the receptacle hoisting cable may be moved away by suitable means from the magnet or a procedure in which both the receptacle hoisting cable and the magnet are moved away from each other by proper means. It is sometimes also possible to accomplish the desired removal of the magnet out of the way of the loading receptacle by de-

positing the magnet in a suitable place of deposit away from the resting place of the loading receptacle. It is then advisable to pay out the magnet hoisting cable and any other cable attached to the magnet or its hoisting cable commensurate with the movement of the crane arm or boom while transporting the loading receptacle to the place of deposit for its load and to take in such hoisting and other cables while the loading receptacle returns. Alternatively, it is possible to sufficiently slacken such hoisting and other cables and to provide for suitable means to pay out and take in such slack as required by the crane arm or boom operation during such transport.

15 The term "hoisting cable," or such similar expression, referred to in the specification and claims is used in its broadest sense and is intended to include any cable, wire, rope, chain or any other means by which an object may be freely suspended from, and lowered and lifted relative to, a given point above such object.

20 The foregoing description is by way of illustration and not of limitation, and we are to be limited only by the appended claims in which we 25 have endeavored to claim broadly all inherent novelty.

We claim:

1. In a device of the crane type for the loading and unloading of magnetic materials, the improvement comprising a loading magnet, a hoisting cable for said magnet, a loading receptacle, a hoisting cable for said receptacle, both said hoisting cables being suspended from a common crane arm in proximity to one another, and means for independently actuating each of said hoisting cables, said magnet and said magnet hoisting cable being wholly independent of said loading receptacle and said receptacle hoisting cable to permit the free lateral movement of said magnet and said receptacle hoisting cable independent of each other.

2. In a device of the crane type for the loading and unloading of magnetic materials, the improvement comprising a loading magnet, a hoisting cable for said magnet, a loading receptacle, a hoisting cable for said receptacle, both said hoisting cables being suspended from a common crane arm in proximity to one another, means for independently actuating each of said hoisting cables and means for moving said magnet and said receptacle hoisting cable apart.

3. In a device of the crane type for the loading and unloading of magnetic materials, the improvement comprising a loading magnet, a hoisting cable for said magnet, a loading receptacle, a hoisting cable for said receptacle, both said hoisting cables being suspended from a common crane arm in proximity to one another, means for independently actuating each of said hoisting cables and means for moving said magnet in a substantially lateral direction away from said receptacle hoisting cable.

4. In a device of the crane type for the loading and unloading of magnetic materials, the improvement comprising a loading magnet, a substantially flexible hoisting cable for said magnet, a loading receptacle, a hoisting cable for said receptacle, both said hoisting cables being suspended from a common crane arm in proximity to one another, means independently actuating each of said hoisting cables, means for moving said magnet together with said magnet hoisting cable in a substantially lateral direction away from said receptacle hoisting cable and means for taking up any slack of said flexible magnet

hoisting cable in a direction away from said receptacle hoisting cable.

5. In a device of the crane type for the loading and unloading of magnetic materials, the improvement comprising a loading magnet, a substantially flexible hoisting cable for said magnet, a loading receptacle, a hoisting cable for said receptacle, both said hoisting cables being suspended from a common crane arm in proximity to one another, means for independently actuating each 10 of said hoisting cables, a cable on said magnet

for swinging said magnet and magnet hoisting cable away from said receptacle hoisting cable, means for lengthening and shortening said cable on said magnet, and a cable on said magnet hoisting cable passing over guide means and connected to a counter weight sufficient to take in any slack of said magnet hoisting cable in a direction away from said receptacle hoisting cable.
